UNITED STATES PATENT OFFICE.

THOMAS H. BARNARD, OF TORONTO, ONTARIO, CANADA.

STRAIN CLAMP.

Application filed August 3, 1922. Serial No. 579,478.

To all whom it may concern:

Be it known that I, THOMAS H. BARNARD, of the city of Toronto, in the county of York, Province of Ontario, Canada, a subject of the King of Great Britain, have invented certain new and useful Improvements in Strain Clamps, of which the following is a specification.

This invention relates to devices commonly called strain clamps which are generally used for anchoring the dead ends of electrical cables, although such devices are in some cases used in various combinations for supporting through cables.

My object is to devise an improved construction for this purpose, which construction may be used for securing the cable, with its armoring, in position, though in cases where additional security is desirable, the armoring may be removed from the core adjacent the end of the cable, and the core itself secured in place in a suitable manner, thus giving much greater security.

I attain my object by means of the constructions hereinafter described and illustrated in the accompanying drawings in which—

Fig. 1 is a longitudinal section through my improved clamp;

Fig. 2 is a plan view of the same; and Fig. 3 a cross section through the same.

In the drawings like numerals of reference indicate corresponding parts in the different figures.

1 is the casing, which will usually be stamped up from the flat sheet into substantially channel form. Between the sides of the channel is supported the bar 2. This bar is held in place by a series of bolts 3

passing through suitable holes in the sides of the casing and the bar. This bar 2 will preferably be inserted endwise of the casing 1, the bar being provided with a groove 4 at each side into which extend tongues 5

stamped out of the sides of the casing. The tongues 5 will preferably be stamped at each side of the casing alternating with the bolts 3. The object of the grooves 4 and tongues 5 will hereinafter appear.

Threaded through the bar 2 are a plurality of bolts or set screws 6. The ends of these screws engage a clamping bar 7, which bar will in practice be placed in position before the bar 2 and be provided with bent ends so that it cannot be withdrawn once the

bar 2 is in position. This bar 7, it will be noted is tapered from end to end.

Below the bar 6 is positioned the wedge member 8, which is provided with a concave under surface to substantially fit the contours of the cable 9.

The device is used by inserting the end of the cable between the under side of the wedge member 8 and the bottom of the casing. When the cable is in position the screws 6 are tightened down against the bar 7 to force the wedge member against the cable to prevent the latter's withdrawal. When the screws 6 are being tightened, there is a tendency to bend the bar 2 upwardly between the bolts 3, hence the provision of the tongues 5 which engage in the grooves 4 to prevent the bending up tendency of the bar 2.

It will also be seen that any pull on the cable 9 will tend to draw the wedge member 8, so that the more the wedge member is moved the tighter is its grip on the cable.

As before stated, it is desirable in some cases to have additional security, and when this is necessary the cable is extended further than usual beyond the end of the bar 7, and from this extending end the armoring or sheathing is removed exposing the core of the cable. The naked core 13 is then bent upwardly around an arc-shaped guide 15 formed at the end of the bar 7 and back over the top of the bar 2 alongside the screws 6. It will be noted that certain of these screws 14 are longer than the others, and slidable on these screws is a clamping plate 10, which is adapted to be forced by nuts 11 on the screws 14 to clamp the core against the upper side of the bar 2.

It will be noted that the bar 2 is somewhat of T-form, the arms of the T being adapted to rest on the tops of the sides of the casing. At the outer edge of the upper surface of each arm of the T is formed a rib or bead 12 to prevent the core 13 slipping from between the plate 10 and the top of the bar 2.

A separate plate 10 may be provided on each bolt 14 if thought desirable, and any number or any size of these plates may be used as may be necessary. The casing 1, bars 2 and 7, and wedge member 8 may be of any desired length to suit the requirements of the case, and any number of bolts 3 and screws 6 may be used.

The clamp will be suitably formed at its

end so that it may be secured to a post or other support.

If desired the bottom of the casing 1 and the under surface of the wedge 7 may be 5 provided with suitable ribs and grooves to give them a better grip on the cable. As the armoring of the cable is usually in the form of a helix, these ribs and grooves will also preferably be of a suitable shape to match 10 the helix of the cable.

From the above description it will be seen that I have devised a strain clamp which will satisfactorily attain the objects of my invention as set out in the preamble of this 15 specification.

What I claim as my invention is:—

1. In a strain clamp for cables, the combination of a channel-shaped casing; a bar lying between the sides of said casing; bolts 20 passing through the sides of said casing and said bar to clamp the latter in position; a clamping bar below said first mentioned bar; and means engaging both sides of said bar for actuating said clamping bar to grip 25 a cable.

2. In a strain clamp for cables, the combination of a channel-shaped casing; a bar secured in and closing the open side of said casing; a tapered clamping bar below said 30 first mentioned bar; a wedging member adapted to fit below the clamping bar; and means for actuating said clamping bar to grip a cable between the wedging member and bottom of the casing.

3. In a strain clamp for cored cables, the combination of a channel-shaped casing; a member supported by the sides of said casing; a screw threaded through the member by means of which a cable may be clamped 40 against the bottom of the casing; and means for independently gripping the core of the cable.

4. In a strain clamp for cables, the combination of a channel-shaped casing; a bar 45 secured in and closing the open side of said casing, said bar having a groove formed in each side thereof and said casing having projections formed thereon engaging in said grooves; a clamping bar below said first mentioned bar; and means for actuating said clamping bar to grip a cable.

5. In a strain clamp for cables, the combination of a channel-shaped casing; a bar secured in and closing the open side of 55 said casing; a clamping bar below said first mentioned bar; screws threaded through the first mentioned bar and adapted to engage said clamping bar, a core clamping plate slidable on one of said screws; and a nut on said screw adapted to force the clamping plate towards the outer surface of the first mentioned bar.

6. In a strain clamp for cables, the combination of a channel-shaped casing; a bar 65 secured in and closing the open side of said

casing; a tapered clamping bar below said first mentioned bar; a wedging member adapted to fit below the clamping bar, screws threaded through the first mentioned bar and adapted to engage said clamping 70 bar; a core clamping plate slidable on one of said screws; and a nut on said screw adapted to force the clamping plate towards the outer surface of the first mentioned bar. 75

7. In a strain clamp for cables, the combination of a channel-shaped casing; a bar secured in and closing the open side of said casing, said bar having a groove formed in each side thereof and said casing having projections formed thereon engaging in said 80 grooves; a tapered clamping bar below said first mentioned bar; a wedging member adapted to fit below the clamping bar; screws threaded through the first mentioned bar and adapted to engage said clamping bar; a core clamping plate slidable on one of 85 said screws; and a nut on said screw adapted to force the clamping plate towards the outer surface of the first mentioned bar.

8. In a strain clamp for sheathed cables, the combination of a channel-shaped casing; a bar secured in and closing the open side of said casing; a clamping bar between said first mentioned bar and the bottom of the channel-shaped casing; screws passing through the first mentioned bar and adapted to engage the clamping bar to clamp a cable between the clamping bar and the bottom of the casing; a clamping plate slidable relative to one of said screws; and a nut on said 90 screw adapted to force the clamping plate towards the outer surface of the first mentioned cable for clamping the cable core between the plate and first mentioned bar, said bar being provided with a rib to prevent 95 side slip of the core.

9. In a strain clamp for cables, the combination of a channel-shaped casing; a bar closing the open side of said casing; bolts securing said bar in position in the casing, 100 said bar having a groove formed in each side thereof and said casing having projections formed therein at each side between each of said bolts; a clamping bar below the first mentioned bar; and screws threaded through the first mentioned bar and adapted to engage the clamping bar. 110

10. In a strain clamp for sheathed cables, the combination of a channel-shaped casing; a bar secured in and closing the open 115 side of said casing; a clamping bar below said first mentioned bar; means for actuating said clamping bar to grip the cable, said clamping bar having an arc-shaped guide at one end around which the core of the cable may be led to the top of the first mentioned bar; and means for clamping the core against the top of the first mentioned bar. 125

11. In a strain clamp for sheathed cables, the combination of a channel-shaped cas- 130

ing; a bar secured between the sides of said casing; a screw threaded through the bar by means of which a cable may be clamped against the bottom of the casing; and means for independently gripping the core of the cable against the top of the said bar.

12. In a strain clamp for sheathed cables, the combination of a channel-shaped casing; a bar secured between the sides of said cas-

ing; a screw threaded through the bar by means of which a cable may be clamped against the bottom of the casing; and means carried by the screw for independently gripping the core of the cable against the top of the said bar.

Signed at Toronto, Canada, this 18th day of July, 1922.

THOMAS H. BARNARD.
